UNITED STATES PATENT OFFICE.

ALEXANDER SVALINA, OF CLEVELAND, OHIO.

COMBINATION-WEAPON.

1,242,265.

Specification of Letters Patent.

Patented Oct. 9, 1917.

Application filed May 23, 1917. Serial No. 170,499.

To all whom it may concern:

Be it known that I, ALEXANDER SVALINA, a citizen of Russia, residing at Cleveland, in the county of Cuyahoga and State of Ohio, have invented certain new and useful Improvements in Combination-Weapons, of which the following is a specification.

This invention has special reference to a combination sword and pistol.

10 One object of the invention is to provide an improved form of combination weapon wherein the pistol grip and the sword grip will be so arranged as to be complementary.

15 A second object of the invention is to provide a combination sword and automatic pistol wherein the pistol grip will have its magazine pocket prevented from accidental opening when the device is used to strike with, as in using the sword, by means of a 20 closure forming part of the sword grip.

A third important object of the invention is to so arrange the barrel of the pistol in a 25 weapon of this description as to form a guard for the sword.

25 With the above and other objects in view, as will be hereinafter apparent, the invention consists of certain novel details of construction and combinations of parts hereinafter fully described, illustrated in the accompanying drawing, and specifically 30 claimed.

In the accompanying drawing, like characters of reference indicate like parts in the several views, and:—

35 Figure 1 is a side elevation of the complete weapon, the scabbard not being shown, as any desired form of scabbard can be used.

Fig. 2 is a section on the line 2—2 of Fig. 1.

40 Fig. 3 is an enlarged detail showing the hilt of the sword with the pistol in position and the magazine pocket opened.

Fig. 4 is a section on the line 4—4 of Fig. 3.

45 In the embodiment of the invention herein illustrated there is disclosed a sword having a blade 10 and a hilt 11. This hilt is recessed or cutaway to receive the grip 12 of a pistol having a barrel 13 projecting at 50 an acute angle to the blade 10. The ar-

rangement of the cutaway portion of the sword hilt is such that when the pistol is in position the pistol handle and sword hilt combined form a proper grip for either the pistol or the sword. Moreover, in order to 5 guard the back of the hand there is provided a basket guard 14 and the knuckles are further guarded by an extension 15 of the trigger guard 16 of the pistol. Now it will be seen by reference to Fig. 3 that the 6 cutaway portion of the sword hilt extends down into the butt thereof and on this cutaway portion is carried a swinging member 16 hinged to the sword hilt as at 17 and provided with the latch 18 arranged to 65 releasably hold the swinging member closed beneath the lower end of the pistol grip 12 wherein the magazine pocket or chamber of the pistol is located. Now by reason of this arrangement the accidental displacement of 70 the magazine from its pocket is prevented when the member 16 is closed since not only does the latch 18 tend to hold the member closed but furthermore the fingers of the user assist in this. However, whenever it 75 be desired to recharge the magazine pocket it is merely necessary to release the latch 18 and throw back the member 16 whereupon access can be had to the magazine pocket aforesaid.

80 There has thus been provided a simple and efficient device of the kind described and for the purpose specified.

It is obvious that many minor changes may be made in the form and construction 85 of the invention without departing from the material principles thereof. It is not therefore desired to confine the invention to the exact form herein shown and described but it is wished to include all such as properly 90 come within the scope claimed.

Having thus described the invention, what is claimed as new, is:—

The combination with a sword having a 95 blade and a grip provided with a recess, of a pistol having a handle seated in the recess complementary to the remainder of the sword grip, said pistol grip having a magazine pocket or chamber opening downwardly along the sword grip, a swinging 100

ember carried by the butt end of the word grip and arranged to close on said word grip beneath said magazine pocket hereby to prevent withdrawal of the magazine, and a latch to hold the swinging member in position to close the pocket.

In testimony whereof I affix my signature.

ALEXANDER SVALINA.
